TRAIN-CONTROL SYSTEM AND APPARATUS

Application filed September 30, 1921. Serial No. 504,436.

This invention relates to train control systems and the apparatus used in connection therewith and has for an object to provide a system of train control which is operated by electromagnetic induction from devices located on the track coacting with devices located on the locomotive and a further object of this invention is the use of a device known as the magnetron used as a medium for receiving an electrical effect from the track device, thereby securing a system which is highly sensitive, operative through a wide margin of safety and operating with a high degree of efficiency and reliability, which are essentials for apparatus of this kind. These and other objects of this invention will be understood from the following specification and the accompanying drawings in which Fig. 1, is an outline drawing showing the working principles of the magnetron as applied in the present invention to produce a retarding effect on the locomotive, Fig. 1a, is a sectional detail with reference to Fig. 1, Fig. 2 is a side elevation of the track device, Fig. 3 is a plan view of the apparatus shown in Fig. 1, complete with the magnetizing coil in place, Fig. 4 is another form of magnetron and applied to give a proceed signal to the locomotive, Fig. 5 is an elevation of the track device as shown in Fig. 2, Fig. 6 is a diagrammatic view showing the principles of the operation of the apparatus in Fig. 4, Figs. 7 and 8 are details indicating the principles of operation of the apparatus with reference to Fig. 6, Fig. 9 is a wiring diagram of one method of applying the apparatus on the locomotive, and Fig. 10 is a wiring diagram of the apparatus as it may be installed in the track. The system as disclosed in this invention includes means for communicating proceed, caution and stop signals to the locomotive, also in combination with the stop signal a means is provided for operating the brake apparatus. The present invention does not disclose a system of speed control, although the apparatus itself can be readily adapted for this purpose to any of the well-known speed control systems heretofore proposed either using a centrifuge device or a device

operating on a time interval basis from track devices of varying lengths.

The effects which operate the signal apparatus on the locomotive are communicated from the track according to track conditions by electromagnetic induction and the apparatus may be described under two headings, i. e., that which produces a retarding or stop effect on the locomotive, known as the stop apparatus and that which produces a proceed effect on the locomotive known as the proceed apparatus. The stop and proceed apparatus make use of a device known as a magnetron which is a vacuum tube device, responsive to the principles of electromagnetic induction and the track device is provided with a suitable apparatus to influence both the stop and proceed apparatus on the locomotive inductively. The magnetron which is used in the present invention works on the principle of the apparatus described in the Journal of the American Institute of Electrical Engineers, volume 40, number 9, page 715. This device is popularly known as a "vacuum tube device"; and "electron tube" or a "space current device," of which a variety of forms are commercially available.

The track apparatus will be understood from the illustration shown in Figs. 2 and 5, in which 11 and 12 are two parallel bars of magnetic iron placed on the track, parallel with the running rails and having at intervals a core 13 connecting the poles 11 and 12, and provided with a coil 14. Any number of these coils may be provided and may be connected in series or in series multiple. For the purpose of the present invention the coils are so connected that one of the magnetic bars becomes a north pole and the other becomes a south pole when the coils are energized and when these coils are deenergized, there is no magnetism in these bars. The track device is sloped or ramped at each end and is sometimes referred to as a track ramp, although no physical contact is made between it and the locomotive apparatus, for the purpose of the present invention.

The stop apparatus will be understood by a study of Figs. 1, 1a and 3. This consists of a glass tube 21 which has been vacuumed

and placed between the poles 16 and 18. Pole 16 has an extended pole piece 15, arranged to intercept the vertical plane of the magnetic bars 11 and 12, as indicated in Fig. 5 3 and the pole 18 has a corresponding pole piece 17. These pole pieces are held in position with respect to each other by the non-magnetic bars 19 and 20. The glass tube 21 is provided with a metallic cylindrical anode 10 24 and a filament 23, passing through the centre; also with a magnetizing coil 22 on the outside. The operation of the apparatus requires that the filament or cathode be heated and for this purpose as well as for energizing 15 coil 22, the battery 26 is provided having one pole connected to the cathode wire 23 and the other pole connected to coil 22. The opposite end of coil 22 connects to the opposite end of the cathode wire. This arrangement, 20 therefore, connects battery 26 in series with the cathode wire and the magnetizing coil 22, thus maintaining the temperature of the cathode and creating a magnetic flux in the tube.

25 Relay 30 connects by wire 29 to the cathode 23 and by wire 28 connects to battery 27 and to the anode 24. If, therefore, a circuit is established between the anode and the cathode inside the vacuum tube, relay 30 will 30 be energized from battery 27 and if this circuit is interrupted, relay 30 will be de-energized.

A well-known principle of vacuum tubes is that when the cathode is heated and a voltage is impressed between the anode and cathode, a circuit is established between them as occurs in the present case, between 23 and 40 24. This circuit, however, is influenced by an exterior magnetic field in the following manner:

When the magnetic flux generated by the coil 22 is below a certain critical value, the electrons discharged from the cathode traverse a path as indicated by the dotted lines 45 in the lower illustration in Fig. 1a. When, however, the flux generated in coil 22 exceeds this critical value, the electrons traverse paths similar to the upper illustration in Fig. 1a. In the former case, it will be noted 50 that the electrons pass from the cathode to the anode and therefore establish a circuit, but in the latter case, they turn back upon themselves and do not reach the anode and therefore fail to establish a circuit. The change 55 from one of these conditions to the other in practice occurs abruptly so that the operation of the apparatus is reliable and efficient at the critical value the paths of the electrons becoming tangent to the anode.

60 The illustration in Fig. 3 shows the vacuum tube inserted in jaws formed in the poles 16 and 18. This is for convenience in inspecting and replacing tubes. The coil 22 generates a flux which energizes the poles 65 16 and 18 and also the space between these

poles. This flux, however, is below the pre-determined value which will open the circuit between the anode and the cathode. As soon, however, as the pole pieces 15 and 17 pass through the vertical planes of the magnetic plates 11 and 12, the flux from the magnetizing coil 22 is thereby greatly strengthened, due to the reduction in the air gap between these pole pieces. This in turn increases correspondingly the flux through the vacuum tube 21, thereby setting up the conditions which cause the circuit to open between the anode and the cathode and thus deenergizes the block relay 30, during the time that this device is passing over the track ramp. The track ramps are usually placed on a higher plane than the top of the running rails so that when this device passes over the rails themselves at a cross-over or switch, the air gap is so much greater that the device is not falsely operated thereby.

The magnetron illustrated in Fig. 4 is applied to establish a circuit when the locomotive passes over a track ramp and therefore works on the reverse principle, to that described in Fig. 1. This device consists of a pole 36 having a pole piece 35, aligning with the magnetic plate 11 and an opposing pole 38 having the pole piece 37, aligning with the magnetic plate 12. These poles are held in alignment by the non-magnetic bar 39. Between these pole pieces the vacuum tube 31 is placed, having a hot wire cathode 42 and two separate sets of anode plates 44 and 45 which are insulated from each other by 40 the insulation 43. These are spaced around the tube as indicated in Fig. 6. The cathode 42 connects to wire 52, battery 55 and by wire 56 to the other end of the cathode, thus permanently heating the cathode wire from battery 55 as indicated in Fig. 4. Relay 53 it will be noted, has a differential winding, the central point connecting by wire 50 to battery 51 and the other side of this battery connects by wire 52 to the cathode 42. One end of the differential winding connects by wire 48 to the anode 44 and the other end of the differential winding connects by wire 49 to the anode 45. If a circuit is established from the anode to each of the cathodes then each coil of the differential winding will be equally energized thereby neutralizing each other and the armatures of this relay will not be moved. On the other hand, if a circuit is established from the cathode to the anode 44, then relay 53 will be energized with a certain polarity, attracting the neutral armature 61 and moving the polarized armature 62 in accordance with the polarity of the magnetizing coil. Also, if a circuit is established from the cathode 42 to the anode 45, relay 53 will be energized with opposite polarity by the other coil, attracting armature 61 and moving the polarized armature into the opposite position. The first condi-

tion is established as indicated in Fig. 6, when the electrons pass from the cathode 42 in equal numbers to each set of anode plates 44 and 45, as shown by the dotted lines. From Fig. 6, it will be noted that all the anode plates 44 on one side of the insulation 43 are connected in multiple to the wire 46 and all the anode plates 45 on the opposite side of this insulation are connected in multiple to the wire 47, connecting respectively to the wires 48 and 49 which are the leads of the differential relay 53.

The path of the electrons is influenced by the magnetic lines of force in a manner similar to the conductors in a motor armature, generally known as "Fleming's rule." A magnetic field in one direction causes the electrons to traverse curved paths so that when they pass from the cathode 42 to the anode 45, for instance, as illustrated in Fig. 7, they are moved away from the anode 44, and when the magnetic field is in the reverse direction, they traverse paths as illustrated in Fig. 8, from the cathode 42 to the anode 44 and move away from the anode 45.

The application of this principle will be understood by considering the track magnet in Fig. 5, in combination with the arrangement shown in Fig. 4. When the coil 14 is energized, for instance, a magnetic flux is impressed upon the pole pieces 35 and 37 by electromagnetic induction, thereby setting up a field between the poles 36 and 38. When the pole 36 is energized with north polarity then the electrons may set up the condition corresponding to Fig. 7, establishing a circuit between the cathode 42 and the anode 45 and when pole 38 is energized with north polarity, this may set up the conditions corresponding to Fig. 8, establishing a circuit between the cathode 42 and the anode 44. It will thus be noted that under normal conditions, when the magnetron 41 is not over a ramp or is passing over a de-energized ramp, the electrons pass equally between the cathode and the two sets of anode plates, thus setting up a circuit in the differential relay which neutralizes itself. As soon as this magnetron passes over a ramp which is energized so as to induce a north polarity in pole 36, then a circuit is established from the cathode to the anode plate 45, thereby energizing one coil of relay 53 and deenergizing the other coil connected to the anode plate 44, giving this relay a definite polarity and under the same conditions when the polarity of the track device is reversed energizing the pole 38 with north polarity, then the circuit between the cathode and the anode 45, is interrupted and a circuit is established between the cathode and the anode 44, thus energizing the other coil of the differential relay and thereby reversing its polarity. The arrangement is thus equivalent to a polarized system, operating the

relay, however, without contacts and with a high degree of reliability, notwithstanding the large air gaps in the magnetic circuit of the poles 36 and 38. Should the magnetism of the track magnet 14 become excessive, the electrons might establish a condition similar to Fig. 1a, (top view); this however, is very unlikely to occur due to the air gap in the circuit of the track magnet. If it did occur it would merely deenergize relay 53 and prevent a clear signal being received.

It will be noted in connection with the stop device shown in Figs. 1 and 1a that the cylindrical anode 24 has a gap on the lower side 25, beneath the cathode wire 23. An object of this gap is to guard against the wire 23, making a short circuit with the anode 24 in case the wire should become broken. The broken ends in this case, will fall through the gap to the glass walls of the tube. Also, it will be noted that the magnetizing coil 22 is connected in series with the cathode wire 23 so that in case the magnetizing coil is disconnected, the cathode is deenergized and cools off and thus becomes inoperative to establish a circuit.

The application of these devices on a locomotive will be understood by a study of the circuit arrangement shown in Fig. 9. In this case a proceed device is placed on each side of the stop device and these proceed devices are connected in multiple circuit. This insures that a proceed device will always engage the track device after the stop device has passed over the track device when the locomotive runs either end first. The multiple arrangement also insures less resistance in the operation of the circuits. The central point of differential relay 53 connects to battery 51 and by wire 52 connects to the cathode of each of the proceed devices. Wires 48 and 49 connect each of the outer ends of the coil windings of relay 53 to the two sets of anodes of the proceed devices as shown in Fig. 4. This causes relay 53 to be energized when proceed devices pass over an energized ramp and also causes the polarized armature 62 to respond to the direction of polarity in the track device. It should be noted that relay 53 is herein regarded as deenergized when the neutral contacts 61—61a are in the lowered position.

Relay 30 as shown in Fig. 9 has a stick circuit and a pick-up circuit. The pick-up circuit can be traced from wire 72, battery 27, wire 71, contact 61 of relay 53 and wire 73. This picks up relay 30 each time that relay 53 closes contact 61. The stick circuit for this relay can be traced from wire 74, contact 75, wire 76, stop device 21 and wire 77 to wire 71. As long as a circuit is established between wires 76 and 77, through the stop device 21, relay 30 remains energized. It has been shown, however, that this circuit is interrupted each time the stop device passes

- over the magnetic plates of a track ramp. Thus, the stick circuit for relay 30 is interrupted on each track ramp encountered and the pick-up circuit must be established at each ramp in order to maintain the proceed effect. This is a circuit arrangement commonly used in systems of this kind. 89 is a cab signal device energized by wire 80, battery 81, wire 82, contact 83 of relay 30 when said relay is energized, wire 84, contact 61a of relay 53 deenergized, polarized contact 62 in the right hand position, wire 85 to the green light "G", thus giving a proceed signal. Another circuit is established "when the polarized armature 62 changes to the opposite position" through wire 86 to the yellow light "Y" and a third circuit is established "when relay 30 is deenergized" through wire 87 to the red light "R". This gives a green or proceed signal when relay 30 is energized and the armature 62 has been moved to a predetermined position, a yellow or caution signal when relay 30 is energized and the armature 62 has been moved to another predetermined position, and a red or stop signal when relay 30 is deenergized. Thus, the signal device 89 is operated in response to the characteristics of the current energizing the trackway device 14.
- 30 An arrangement may be provided in combination with this system for operating the train brakes including the brake valve 88 operated by magnet yoke 120 energized over a circuit including wire 80, battery 81, wire 82, contact 83 and wire 84. This magnet remains energized and holds the valve 88 closed while a proceed or caution signal is established but is deenergized and opens the valve when a red or stop signal has been received.
- 40 Various combinations in the application of the brake valve are usually adopted to meet the operating condition of a railroad and are sufficiently well-known without being illustrated in detail in connection with the present invention. Armature 121 rotates between the poles of the yoke 120 and carries a crank which raises arm 123 to close the valve when in the position shown in full lines but when in the position shown by the dotted lines, this valve is opened. A counterweight 124 is provided on the crank arm giving it a bias to the dotted position. It will be noted that this armature will take up a position on either side of the vertical centre when the yoke is energized and in normal operation when deenergized takes up the dotted position to be held in this position after the yoke is energized. For the purpose of closing the valve therefore, a manually operated resetting plunger 122 is provided which engages the crank arm 124 and swings the armature into the position shown by the full lines where it is held as long as the yoke is energized. A quick stroke of plunger 122 gives the armature its initial start but the inertia of the

armature carries it over the vertical centre to the position shown, which closes the valve. By this arrangement it will be noted that each time the yoke 120 is deenergized the valve is opened and remains open after this yoke is energized again until it is manually reset; also that if the resetting plunger were held in the released position it would not prevent the valve from opening. It should be noted that by controlling the proceed and caution signals through a back contact of relay 53, that in case this relay should become energized improperly, this will immediately extinguish the proceed or caution signal.

The track arrangement is illustrated in Fig. 10, in which the track rails 91 and 92 are shown divided into sections A, B and C, by insulated joints. Each section has a track battery 93 at one end and a track relay 94 at the opposite end, connected by wires 96 and 95 to the track rails 91 and 92, according to the usual track circuit arrangement. The ramps 11 are energized by coils 14 controlled by wire 111, contact 110 of the track relay 94, wire 109 and polarized contact 106 of line relay 97. When this contact is in one position, the coil 14 is energized through wire 112 from battery 107 and when contact 106 is in the opposite position, coil 14 is energized from battery 108. Opposite poles of batteries 107 and 108 are connected to wire 112, thereby changing the direction of current to coil 14 in accordance with the position of contact 106. Line relay 97 connects to the common wire 98 and is controlled by wire 99, contact 100 of track relay 94, wire 101 and contact 102 of the track relay for the next succeeding block, wire 103 and battery 104. This causes contact 106 to move to one position and when the track relay 94 for the next succeeding block is deenergized, contact 102 connects to battery 105, having opposite polarity to battery 104, thereby changing the position of contact 106 and thus changing the polarity of the current energizing coil 14. When the track relay for the block immediately in advance of the ramp is deenergized, the circuit of coil 14 is interrupted at contact 110, and consequently the ramp is deenergized so as to cause a stop signal; when this block is clear and the next succeeding block is occupied the polarity of the current in the line relay 97 is in a direction to energize coil 14 with a polarity which will give a caution signal. When the two blocks immediately ahead of the ramp are clear, the polarity to the coil 14 is in the proper direction to give a proceed signal to the locomotive apparatus.

The device on the vehicle responsive to the track devices has been designated the "magnetron" as its operation is associated with magnetism. This magnetism is obtained from the track by induction and in the draw-

ings a magnetic ramp 11 is shown by means of which the magnetic field on the track is translated to influence the vehicle devices. It is apparent that the magnetron will respond to a magnetic field from any source and is not limited to the particular type of magnet shown. A magnetic field therefore that is controlled corresponding to magnet 11 is the equivalent of this device and should be so understood in the specification and claims.

This invention shows certain novel applications and developments of the magnetron itself, particularly in its application for controlling circuits in response to polarity.

15 Certain features divided out of this application are the subject of a divisional application, Serial No. 196,548, filed June 4, 1927.

This application is the prevailing application in interferences Nos. 51,926; 54,832 and 20 55,029 in which it has been involved.

The form of my invention described includes certain novel arrangements of apparatus on the train and certain novel constructions on the trackway. To some extent 25 the trackway apparatus co-operates with the specific locomotive apparatus shown, but in general, the locomotive apparatus can be applied with a variety of types of trackway apparatus such as will produce the controlling 30 effects on the locomotive apparatus described; also, the trackway apparatus may be used to operate other arrangements of locomotive apparatus from that shown, it is to be understood, therefore, that this invention 35 covers a full range of equivalents for the apparatus and arrangements shown, both on the trackway and on the train, and is not to be limited except as defined in the claims.

Having thus described my invention, I 40 claim:

1. In combination, a railway track, a vehicle thereon, a magnetic device on said track, a vacuum tube device on said vehicle coacting with said track device and a circuit on said vehicle associated with said vacuum tube.

45 2. In combination, a railway track, a vehicle thereon, a magnetic device on said track, a vacuum tube device on said vehicle responsive to the magnetism of said track device and a circuit on said vehicle associated with said vacuum tube device.

50 3. In combination, a railway track, a vehicle thereon, a magnetic device on said track, a vacuum tube device on said vehicle responsive to the magnetism of said track device, an inactive translating device associated with the circuit of said vacuum tube device and means for rendering said translating device active by the magnetism from said track device.

55 4. In combination, a railway track, a vehicle thereon, a magnetic field on said track, a vacuum tube device on said vehicle, a circuit on said vehicle associated with said vacuum tube device, a translating device energized

only by said circuit and means for operating said translating device in response to the polarity of the current energizing said field.

5. In combination, a railway track, a vehicle thereon, a magnetic device on said track, a vacuum tube device on said vehicle, a circuit on said vehicle associated with said vacuum tube device, a polarized relay operatively connected with said circuit, said relay responding to the polarity of the current.

75 6. In combination, a railway track, a vehicle thereon, a magnetic device on said track, a vacuum tube device on said vehicle, a circuit on said vehicle associated with said vacuum tube, a relay operatively connected with said circuit and means for controlling a circuit by said relay when said vacuum tube device is magnetized from said track device.

80 7. In combination, a railway track, a vehicle thereon, a magnetic device on said track, a vacuum tube device on said vehicle coacting with said magnetic device, a circuit associated with said vacuum tube device and means for deenergizing said circuit when said vehicle device passes through the vertical plane of said track device.

85 8. In combination, a railway track, a vehicle thereon, a magnetic device on said track, a vacuum tube device on said vehicle, a coil for magnetizing said device, a circuit on said vehicle associated with said vacuum tube device and means for deenergizing said circuit when said vehicle device comes under the influence of said track device.

90 9. In combination, a railway track, a vehicle thereon, a vacuum tube device on said vehicle, means for impressing a magnetic flux on said vacuum tube device, a circuit associated with said vacuum tube and means on said track affecting said magnetic flux, whereby said circuit is deenergized.

95 10. In combination, a railway track, a vehicle thereon, a vacuum tube device on said vehicle, a circuit associated with said vacuum tube, a device on said track and means for impressing a magnetic flux from said track device upon said vacuum tube device, thereby affecting the operation of said circuit.

110 11. In combination, a railway track, a vehicle thereon, a vacuum tube device on said vehicle having a pair of poles, a circuit associated with said vacuum tube device, a device on said track and means for magnetizing said poles from said track device, thereby affecting the operation of said circuit.

115 12. In combination, a railway track, a vehicle thereon, a vacuum tube device on said vehicle having a pair of poles, a circuit associated with said vacuum tube device, a device on said track having a pair of poles and means for magnetizing the poles of said vehicle device in response to the poles of said track device, thereby affecting the operation of said circuit.

13. In combination, a railway track, a vehicle thereon, a vacuum tube device on said vehicle, said device having a separate pair of anodes and a cathode, circuits with a translating device associated with each of said anodes and said cathode, a magnetic device on said track and means whereby the magnetism of said track device affects the operation of said translating device. 70
14. In combination, a railway track, a vehicle thereon, a vacuum tube device on said vehicle, said device having a separate pair of anodes and a cathode, circuits associated with each of said anodes and said cathode, a magnetic device on said track and means whereby the magnetism from said track device interrupts the circuit from one of said anodes to said cathode. 75
15. In combination, a railway track, a vehicle thereon, a vacuum tube device on said vehicle, said device having a separate pair of anodes and a cathode, circuits associated with each of said anodes and said cathode, a magnetic device on said track and means whereby the magnetism of one polarity from said track device will interrupt the circuit from one of said anodes to said cathode and magnetism of the opposite polarity will interrupt the circuit from the other of said anodes to said cathode. 80
16. In combination, a railway track, a vehicle thereon, a vacuum tube device on said vehicle, said device having a plurality of anodes grouped in opposite sets and insulated from each other and a cathode, circuits associated with each set of anodes and said cathode, a magnetic device on said track and means whereby the magnetism of said track device independently affects each of said circuits. 85
17. In combination, a railway track, a vehicle thereon, a vacuum tube device on said vehicle, said device having a pair of longitudinal anodes separated by an insulating plate and a cathode, circuits associated with each of said anodes and said cathode, a device on said track and means for controlling said track device whereby the circuit between said cathode and either of said anodes may be interrupted. 90
18. In combination, a railway track, a vehicle thereon, a vacuum tube device on said vehicle, said device having a pair of longitudinal anodes separated by an insulating plate and a cathode, circuits associated with each of said anodes and said cathode, a differential relay included in said circuits, a device on said track and means for controlling said track device whereby the current in either side of said differential relay may be increased over the current in the other side. 115
19. In combination, a railway track, a vehicle thereon, a vacuum tube device on said vehicle, said device having a separate pair of anodes and a cathode, a differential relay, one winding of said relay connecting to each of said anodes and the neutral point of said winding connecting to said cathode and to a battery and means on the track for varying the current to each winding of said relay. 120
20. In combination, a railway track, a vehicle thereon, a vacuum tube device on said vehicle, said device having an anode and a cathode, a coil for supplying a magnetic field for said device, said coil connected in series with said cathode, a circuit associated with said anode and cathode and means on the track for varying said magnetic field. 125
21. In combination, a railway track, a vehicle thereon, a vacuum tube device on said vehicle, said device having an anode and a cathode, a coil for supplying a magnetic field for said device, means whereby said coil is de-energized when said cathode is disconnected, a circuit associated with said anode and cathode and means on the track for varying said magnetic field. 130
22. In combination, a railway track, a vehicle thereon, a vacuum tube device on said vehicle, said device having an anode and a cathode, a coil for supplying a magnetic field for said device, said device having a cylindrical anode with a longitudinal gap in its lower side, a cathode in the centre of said anode, a circuit including a translating device associated with said anode and cathode, a magnetic device on the track and means whereby said track device varies the current in said circuit. 135
23. In a railway traffic controlling system, in combination, a railway track, a vehicle thereon, a magnetic device on said track controlled by traffic conditions, a vacuum tube device on said vehicle having a circuit, said vacuum tube device coacting with said magnetic device, a control device associated with said circuit and means for operating said control device from said track device. 140
24. In a railway traffic controlling system in combination, a railway track, a vehicle thereon, a device on said track controlled by traffic conditions, a vacuum tube device on said vehicle having magnetizing means and a circuit, a control device associated with said circuit and means for operating said control device to control said vehicle by said track device. 145
25. In a railway traffic controlling system, in combination, a railway track, a vehicle thereon, a device on said track, a vacuum tube device on said vehicle having magnetizing means and a circuit, a stick relay associated with said circuit and means for deenergizing said stick relay by said track device. 150
26. In a railway traffic controlling system, in combination, a railway track, a vehicle thereon, a magnetic device on said track controlled by traffic conditions, a vacuum tube device on said vehicle coacting with said

- track device, a circuit including a stick relay associated with said vacuum tube device, and means for energizing said stick relay when said track device is magnetized.
27. In a railway traffic controlling system, in combination, a railway track, a vehicle thereon, a magnetic field on said track, a plurality of vacuum tube devices on said vehicle, a circuit associated with each of said devices, a translating device controlled by said circuits, said vacuum tube devices responsive to said magnetic field whereby one of said tubes deenergizes said translating device and the other energizes said translating device. 70
28. In a railway traffic controlling system, in combination, a railway track, a vehicle thereon, a device on said track, a plurality of vacuum tube devices on said vehicle, a stick relay on said vehicle having a pick-up circuit and a stick-up circuit, the pick-up circuit associated with one of said vacuum tube devices and the stick-up circuit associated with the other vacuum tube device, means whereby the said stick-up circuit is opened and the pick-up circuit is closed when said tube devices pass over said track device. 80
29. In a railway traffic controlling system, in combination, a railway track, a vehicle thereon, a device on said track controlled by traffic conditions, a controlling mechanism on said vehicle, a vacuum tube device on said vehicle controlling said mechanism to retard said vehicle and another vacuum tube device controlling said mechanism to produce a non-retarding condition on said vehicle, said vacuum tube devices responding to said track device. 85
30. In a railway traffic controlling system, in combination, a railway track, a vehicle thereon, a magnetic device on said track controlled by traffic conditions, a controlling mechanism on said vehicle, a vacuum tube device on said vehicle controlling said mechanism to retard said vehicle and another vacuum tube device controlling said mechanism to produce a non-retarding condition on said vehicle, said first vacuum tube device responding to said track device and said second vacuum tube device responding to the magnetism of said track device. 90
31. In a railway traffic controlling system, in combination, a railway track, a vehicle thereon, a magnetic field on said track controlled by traffic conditions, a cab signal on said vehicle, a vacuum tube device, a circuit associated with said vacuum tube device, a translating device energized solely by said circuit controlling said signal and arranged to give a proceed indication when said track field is magnetized with one polarity and to give a caution signal when said track field is magnetized with opposite polarity. 100
32. In a railway traffic controlling system, in combination, a railway track, a vehicle thereon, a magnetic device on said track controlled by traffic conditions, a cab signal on said vehicle, a vacuum tube device on said vehicle responding to said track device, causing said signal to give a stop indication, and another vacuum tube device on said vehicle responding to the magnetism in said track device to give a caution or clear signal. 105
33. In a railway traffic controlling system, in combination, a railway track, a vehicle thereon, a device on said track controlled by traffic conditions, a controlling mechanism on said vehicle having a retarding and a non-retarding condition, a vacuum tube device on said vehicle responding to said track device and means whereby said vacuum tube device coacting with said track device establishes the retarding condition in said mechanism. 110
34. In a railway traffic controlling system, in combination, a railway track, a vehicle thereon, a device on said track controlled by traffic conditions, a controlling mechanism on said vehicle having a proceed circuit and a stop circuit, a vacuum tube device on said vehicle interrupting said stop circuit and another vacuum tube device establishing said proceed circuit, said vacuum tube devices being responsive to said track device. 115
35. In a railway traffic controlling system, in combination, a railway track, a vehicle thereon, a device on said track controlled by traffic conditions, a cab signal on said vehicle, a vacuum tube device on said vehicle responding to said track device, a differential relay associated with said vacuum tube device, the indication of said signal being controlled by the contacts of said relay when in its neutral condition. 120
36. In a railway traffic controlling system, in combination, a railway track, a vehicle thereon, a device on said track controlled by traffic conditions, a cab signal on said vehicle, a vacuum tube device on said vehicle responding to said track device, a differential relay associated with said vacuum tube device, said differential relay having a neutral armature and means for detecting if the neutral armature of said relay is in the raised position when said vacuum tube device is not under the influence of said track device. 125
37. In a railway traffic controlling system, in combination, a railway track, a vehicle thereon, a magnetic field on said track controlled by traffic conditions, a vacuum tube device on said vehicle, controlling a circuit, said device responsive to said track field and means controlled solely by said circuit for obtaining one effect on said vehicle when said track field is energized by current of one polarity and for obtaining a different effect when it is energized by current of opposite polarity. 130

38. In a railway traffic controlling system, in combination, a railway track, a vehicle thereon, a device on said track controlled by traffic conditions, a device on said vehicle responsive to said track device, a 5 brake valve controlled by said vehicle device, and a manually operated mechanism operating in combination with the inertia of said brake valve for resetting said valve after it has been opened.
- 10 39. In a railway traffic controlling system, in combination, a railway track, a vehicle thereon, a device on said track controlled by traffic conditions, a device on said vehicle responsive to said track device, a 15 brake valve controlled by said locomotive device, and a manually operated mechanism for partially closing said valve and operating in combination with the inertia of said valve for closing the same.
- 20 40. In a railway traffic controlling system, in combination, a railway track, a vehicle thereon, a device on said track controlled by traffic conditions, a device on said vehicle responsive to said track device, an 25 electrically operated brake valve consisting of a rotating armature between a pair of poles, said armature having a neutral zone on a line between said poles and when moved 30 beyond this line in one direction, said valve is opened and when moved in the opposite direction, said valve is closed, said valve being controlled by said vehicle device.
- 35 41. In a railway traffic controlling system, in combination, a railway track, a vehicle thereon, a device on said track controlled by traffic conditions, a device on said vehicle responsive to said track device, an 40 electrically operated brake valve consisting of a rotating armature between a pair of poles, said armature having a neutral zone on a line between said poles and biased to move beyond this line to open said valve and means for manually resetting said armature to the opposite position to close said 45 valve, said valve being controlled by said vehicle device.
- 45 42. In combination, a railway track, a vehicle thereon, a vacuum tube device on said vehicle, said device having an anode and a 50 cathode, a coil for supplying a magnetic field for said device, means whereby said coil is deenergized when said cathode is broken, and a circuit on said vehicle associated with said anode and cathode.
- 55 43. In a railway traffic controlling system, in combination, a railway track, a vehicle thereon, a device on said track, a vacuum tube device on said vehicle responsive to said track device, a circuit associated with said vacuum 60 tube device and a direct current polarized relay operated by said circuit.
- 65 44. In a railway traffic controlling system, in combination, a railway track, a vehicle thereon, a device on said track, a vacuum tube 65 device on said vehicle responsive to said track device, a circuit associated with said vacuum tube device and a relay having opposing windings operated by said circuit.
- 70 45. In a railway traffic controlling system, in combination, a railway track, a vehicle thereon, a device on said track, a vacuum tube device on said vehicle responsive to said track device, a circuit associated with said vacuum tube device and a relay having opposing windings with a polarized armature operated by said circuit.
- 75 46. In combination, a railway track, a vehicle thereon, a magnetic field on said track controlled by traffic conditions, a plurality of vacuum tube devices on said vehicle independently responsive to said track field, a circuit associated with both of said vacuum tube devices and a translating device operated solely by said circuit to the proceed position.
- 80 47. In combination, a railway track, a vehicle thereon, a magnetic field on said track, a plurality of vacuum tube devices on said vehicle responsive to said track field, said tube devices arranged to control a direct current circuit in multiple and a translating device operated by said circuit.
- 85 48. In a railway traffic controlling system, in combination, a railway track, a vehicle thereon, a device on said track controlled by traffic conditions, a vacuum tube device on said vehicle responsive to said track device and controlling a circuit, and a translating device operated by said circuit, said translating device having a polarized element and a neutral element and capable of taking up either of two positions when said translating device is energized.
- 90 49. In a railway traffic controlling system, in combination, a railway track, a vehicle thereon, a device on said track controlled by traffic conditions, a vacuum tube device on said vehicle responsive to said track device and controlling a circuit, a translating device operated by said circuit, said translating device having a polarized element and a neutral element, one of said elements capable of taking up either of two positions and means for positioning said element.
- 95 50. In a railway traffic controlling system, in combination, a railway track, a vehicle thereon, a device on said track controlled by traffic conditions, a device on said vehicle responsive to said track device and controlling a circuit, a translating device operated by said circuit and having an element capable of taking up either of two positions and means in combination with the inertia of said element for moving it to a predetermined position.
- 100 51. In a railway traffic controlling system, in combination, a railway track, a vehicle thereon, a device on said track controlled by traffic conditions, a device on said vehicle responsive to said track device, a signaling de- 105
- 110
- 115
- 120
- 125

- vice on said vehicle, a differential relay having opposing windings controlled by said vehicle device and controlling a stick relay, said stick relay controlling said signal device.
52. In a railway traffic controlling system, in combination, a railway track, a vehicle thereon, means on said track controlled by traffic conditions, a device on said vehicle responsive to said track means operating a translating device, said translating device comprising a pair of poles, an armature pivoted between said poles, said armature having a neutral zone on a line between said poles and capable of being positioned on either side 15 of said neutral zone when said poles are energized.
53. In a railway traffic controlling system, in combination, a railway track, a vehicle thereon, means on said track controlled by 20 traffic conditions, a device on said vehicle responsive to said track means operating a translating device, said translating device comprising a pair of poles, an armature pivoted between said poles, said armature having 25 a neutral zone on a line between said poles, means for positioning said armature and means for magnetizing said poles to hold said armature in position.
54. In a railway traffic controlling system, 30 the combination of a railway track, a vehicle thereon, means on said track controlled by traffic conditions, a device on said vehicle responsive to said track means, a relay with opposing windings controlled by said 35 device, and means for varying the current in both of said windings by said track means.
55. In a railway traffic controlling system, 40 the combination of a railway track, a vehicle thereon, means on said track controlled by traffic conditions, a device on said vehicle responsive to said track means, a relay with opposing windings controlled by said device, said relay having two independent armatures, one of said armatures positioned by 45 the difference of the currents in said windings and the other armature being attracted when said relay is energized.
56. In a railway traffic controlling system, 50 the combination of a railway track, a vehicle thereon, means on said track controlled by traffic conditions, a device on said vehicle responsive to said track means, a relay with opposing windings controlled by said device, said relay controlling a circuit and having 55 two independent armatures, one of said armatures positioned by the difference of the currents in said windings, said armatures controlling said circuit in series.
57. In a railway traffic controlling system, 60 the combination of a railway track, a vehicle thereon, means on said track controlled by traffic conditions, a device on said vehicle responsive to said track means, a controlling circuit, a relay having two independent armatures one of said armatures positioned by 65 the difference of the currents in said windings and controlling said circuit and the other armature controlling said circuit in the deenergized position.
58. In a train control system, in combination, a vehicle carried mechanism including an electron discharge device and roadside mechanism for magnetically influencing the electron discharge device for producing any one of three different indications in the 70 vehicle carried mechanism.
59. In a train control system, in combination, vehicle carried mechanism including a magnetron means and roadside mechanism for magnetically influencing the magnetron means for producing any one of three different 75 indications in the vehicle carried mechanism.
60. In a train control system, in combination, vehicle carried mechanism including an electron discharge device and traffic controlled roadside mechanism for magnetically influencing the electron discharge device for producing any one of three different indications in the vehicle carried mechanism.
61. In a train control system, in combination, vehicle carried mechanism including means operable for placing the train under a speed restriction and an electron discharge device of which a magnetic field is a 80 controlling component for controlling the operation of said means, and roadside mechanism for influencing the electron discharge device for producing any one of three different indications in the vehicle carried mechanism.
62. In a train control system, in combination, vehicle carried mechanism comprising means movable into three different positions for producing "clear", "caution" and "danger" train indications and instrumentalities including a magnetron for controlling the operation of said movable means, and roadside mechanism operable in accordance with "clear", "caution" and "danger" track conditions for magnetically influencing said device and for operating said instrumentalities 95 in any of three different ways for selectively producing any of said train indications.
63. In a train control system, in combination, vehicle carried mechanism including 100 means selectively operable for placing the train under a speed restriction and for permitting unlimited speed thereof and a magnetron for controlling the operation of said means, and roadside mechanism for magnetically influencing the magnetron for producing the controlling operations thereof.
64. In a train control system, in combination, vehicle carried mechanism including means operable for placing the train under 115 a speed restriction and an electron discharge device of which a magnetic field is a controlling component operable for controlling the operation of said means.
65. In a train control system, in combina- 120

- tion, vehicle carried mechanism including means operable for placing the train under a speed restriction and a magnetron for controlling the operation of said means.
66. In combination, a vehicle circuit including an electron discharge device of which a magnetic field is a controlling component and roadside mechanism for influencing the said device for affecting the circuit. 5
67. In combination, a vehicle circuit including an electron discharge device of which a magnetic field is a controlling component and roadside magnet mechanism for magnetically influencing the said device for affecting the circuit. 10
68. In combination, a vehicle circuit including a magnetron and roadside mechanism associated therewith for controlling the activity of the magnetron. 15
69. In combination, a vehicle circuit including an electron discharge device of which a magnetic field is a controlling component, road side mechanism for influencing the said device to change the characteristic of the circuit and means for maintaining the circuit changed after the device is so influenced. 20
70. In combination, a normally active vehicle magnetron circuit and roadside magnetic means directly influencing said circuit for deenergizing the same. 25
71. In combination, a vehicle circuit including a normally open thermo-ionic device of which a magnetic field is a controlling component and roadside mechanism operative magnetically thereon for closing the same. 30
72. In combination, a railway track, a vehicle thereon, a vacuum tube device on said vehicle having poles, a circuit connected to the electrodes of said tube, said circuit established when said tube is under the influence of a magnetic field, a circuit for energizing said poles and means on the track for increasing the magnetic field through said tube. 35
73. In combination, a railway track, a vehicle thereon, a magnetic ridge on said track, a vacuum tube device on said vehicle having a pair of poles, a circuit connected to the electrodes of said tube and established when said tube is under the influence of a magnetic field, means for energizing said poles and means on the track for increasing the magnetic flux through said tube. 40
74. A railway traffic controlling system comprising a magnetron, traffic controlled means for magnetically affecting the electrical conductivity of said magnetron, and traffic governing means controlled by said magnetron. 45
75. A railway traffic controlling system comprising a magnetron, means controlled by current in the track rail for magnetically affecting the electrical conductivity of said magnetron, and traffic governing means controlled by said magnetron. 50
76. In combination, railway traffic governing mechanism including a magnetron, and traffic controlled means for magnetically influencing said magnetron. 55
77. In combination, railway traffic governing mechanism including a magnetron, a track circuit, and means controlled by the current in said track circuit for magnetically affecting said magnetron. 60
78. In combination, railway traffic governing mechanism including a magnetron, and traffic controlled means for impressing a magnetic flux on said magnetron. 65
79. A railway traffic controlling system comprising a magnetron, a traffic controlling circuit including said magnetron, and traffic controlled means for impressing a magnetic flux on said magnetron to effect the operation of said circuit. 70
80. In combination, a railway traffic controlled circuit including an electron discharge device of which a magnetic field is a controlling component, and traffic controlled means for magnetically influencing said device for affecting said circuit. 75
81. Railway traffic controlling apparatus comprising traffic governing means, and a magnetron for controlling the operation of said means. 80
82. In a railway traffic controlling system, in combination, a railway track, a vehicle thereon, trackway means for producing magnetic effects, a plurality of vacuum tube devices on said vehicle responsive to said magnetic effects, a circuit associated with each of said devices, a translating device controlled by said circuits and means whereby one of said vacuum tube devices operates to deenergize said translating device and the other vacuum tube device operates to energize 90 said translating device. 100
83. In combination, a railway track, a vehicle thereon, a magnetic field produced on the trackway by direct current, a pole changer controlling the polarity of said field, a space current device on said vehicle, a circuit on said vehicle associated with said space current device, a translating device operatively connected with said circuit and means including said space current device for operating said translating device in response to the polarity of said field. 105
84. In a railway traffic controlling system, in combination, a railway track, a vehicle thereon, a magnetic field produced on the trackway by direct current and controlled by traffic conditions, a pole changer controlling the polarity of said field, a cab signal on said vehicle, a space current device controlling said signal and arranged to give a proceed indication when said track field is magnetized with one polarity and to give a caution signal when said track field is magnetized with the polarity in the opposite direction. 110
- 85

85. In a railway traffic controlling system, in combination, a railway track, a vehicle thereon, a magnetic field produced on the trackway by direct current and controlled by traffic conditions, a pole changer controlling the polarity of said field, a space current device on said vehicle controlling a circuit, said device responsive to said track field and means for obtaining one effect on said vehicle when said track field is energized by current of one polarity and for obtaining a different effect when said track field is energized by current of opposite polarity.

10 86. In combination, a railway track, a vehicle thereon, a magnetic field on the trackway produced by direct current and controlled by traffic conditions, a plurality of electron tube devices on said vehicle independently responsive to said track field, a circuit associated with said electron tube devices and a translating device operated by said circuit.

15 87. In combination, a railway track, a vehicle thereon, trackway means producing a magnetic field by direct current, a space current device on said vehicle, a circuit on said vehicle associated with said space current device, a translating device operatively connected with said circuit and means associated 20 with said translating device operating in response to the polarity of the current energizing said field.

25 88. In combination, a railway track, a vehicle thereon, trackway means producing a magnetic field controlled by traffic conditions, a plurality of electron tube devices on said vehicle independently responsive to said trackway field, a circuit directly associated with both of said electron tube devices and 30 a translating device operated solely by said circuit to the proceed position.

35 89. In a railway traffic controlling system, the combination, a railway track divided into blocks, a vehicle thereon, trackway means energized by a single circuit producing a magnetic field, said single circuit controlled by said blocks, an electron tube device on said vehicle controlled by said single circuit, a circuit associated with said electron tube 40 device, a translating device controlled only by said last named circuit and means associated with said translating device operating in response to the polarity of the current energizing said field.

45 90. In a railway traffic controlling system, in combination, a railway track, a vehicle thereon, trackway means for producing magnetic effects, a plurality of electron tube devices on said vehicle responsive to said magnetic effects, a circuit associated with each of said devices, a translating device controlled by said circuit, said electron tube devices being so connected that one of said devices operates to deenergize said translating device

while the other device operates simultaneously to energize said translating device.

46 91. In a railway traffic controlling system, in combination, a railway track, a vehicle thereon, a device on the trackway controlled by traffic conditions, a device on the vehicle inductively responsive to said trackway device, a normally energized relay on the vehicle controlled by said vehicle device and deenergized by said trackway device, a translating device on said vehicle electrically energized in the proceed position, a second relay on said vehicle operated by said track device and when energized closing a circuit to energize the first mentioned relay, said relay controlling said translating device and means whereby the circuit of said translating device is established by a back contact on said second relay in the deenergized position.

47 92. In a railway traffic controlling system, in combination, a railway track, a vehicle thereon, a device on the trackway controlled by traffic conditions, a device on the vehicle inductively responsive to said trackway device, a normally energized relay on the vehicle controlled by said vehicle device and deenergized by said trackway device, a translating device on said vehicle electrically energized in the proceed position, a second relay on said vehicle which, when energized, 50 closes a circuit to energize the first named relay and when deenergized operating by a back contact to close a circuit to said translating device.

48 93. In a railway traffic controlling system, in combination, a railway track, a vehicle thereon, a device on the trackway controlled by traffic conditions, a device on the vehicle inductively responsive to said trackway device, a normally energized relay on said vehicle controlling its own circuit and controlled by said vehicle device and deenergized by said trackway device, a translating device on said vehicle electrically energized in the proceed position, a second relay on the vehicle arranged to shunt the control of the normally energized relay where it is controlled by itself and when deenergized, operating to establish the circuit of said translating device.

49 94. In a railway traffic controlling system, in combination, a railway track, a vehicle thereon, a device on the trackway controlled by traffic conditions, a device on said vehicle inductively responsive to said trackway device, a normally energized relay on said vehicle controlled by said vehicle device and deenergized by said trackway device, a second relay on said vehicle controlling said normally energized relay and a translating device on said vehicle controlled by said normally energized relay in the proceed position and said second relay in the deenergized position to operate said translating device to the proceed position.

95. In a train controlling system, the combination, a vehicle with a controlling mechanism having an operative and an inoperative position, a device for resetting said mechanism from the operative to the inoperative position and means co-operating with the inertia of said device for operating said mechanism to the inoperative position.

96. In a train controlling system, the combination, a vehicle with a controlling mechanism, a circuit controlling said mechanism, an electron tube controlling said circuit and operating to close said circuit when energized below a critical value and operating to open said circuit when energized above this value and means on the trackway for energizing said tube.

97. In combination, a railway traffic governing mechanism, a circuit controlling said mechanism, an electron tube controlling said circuit and operating to complete said circuit when energized below a critical value and operating to open said circuit when energized above this value.

98. Railway traffic controlling apparatus comprising traffic governing means, a circuit controlling said means and a magnetron controlling said circuit and arranged to open said circuit when energized above a critical value.

99. In a train controlling system, the combination, a track with a vehicle thereon, a device on the trackway controlled by traffic conditions, a device on the vehicle responding to said trackway device, a controlling mechanism on said vehicle and a circuit controlling said mechanism, said vehicle device controlling said circuit and operating to complete said circuit when energized below a critical value and operating to open said circuit when energized above the critical value.

100. In a railway traffic controlling system, the combination, a railway track divided into blocks, trackway means energized by a single circuit for producing a magnetic field having different characteristics controlled by said blocks, an electron tube device on said vehicle responding to said magnetic field, a circuit controlled by said electron tube device in accordance with the characteristics of said field and a translating device controlled only by said last named circuit in accordance with traffic conditions in said blocks.

101. In a railway traffic controlling system, the combination, a railway track divided into blocks, trackway means energized by a single circuit for producing a magnetic field having different characteristics controlled by said blocks, an electron tube device on said vehicle responding to said magnetic field, a circuit controlled by said electron tube device in accordance with the characteristics of said field and a translating device controlled only by the last named circuit and

selectively responsive to said characteristics.

102. In a railway traffic controlling system, in combination, a railway track divided into blocks, trackway means energized solely by a single circuit for producing a magnetic field having different characteristics, said circuit controlled by a plurality of said blocks, an electron tube device on said vehicle responding to said magnetic field, a circuit on said vehicle controlled by said electron tube in accordance with the characteristics of said field and a translating device controlled by said vehicle circuit to indicate clear, caution and stop conditions of traffic in said blocks.

103. In a railway traffic controlling system, in combination, a railway track divided into blocks, trackway means energized solely by a single circuit for producing a magnetic field, a relay controlled by a plurality of said blocks arranged to change the characteristic of said circuit, an electron tube device on said vehicle responding to said magnetic field, a circuit on said vehicle controlled by said electron tube in accordance with the characteristic of the current energizing said trackway means and a translating device controlled by said vehicle circuit in accordance with traffic conditions in said block.

104. In a railway traffic controlling system, in combination, a railway track divided into blocks, a track circuit with a track relay for each block, a relay controlled by a plurality of said track relays, trackway means energized by an electric circuit for producing a magnetic field, said last named relay controlling said electric circuit and changing its characteristics in accordance with traffic conditions in said blocks, a single electron tube device on said vehicle inductively responsive to the magnetic field of said trackway means, a circuit on said vehicle controlled by said electron tube device in accordance with the characteristic of the circuit energizing said trackway means and a translating device selectively operated by said vehicle circuit in accordance with traffic conditions in said blocks.

105. In a railway traffic controlling system, in combination, a railway track divided into blocks, a track circuit with a track relay for each block, trackway means energized by an electric circuit for producing a magnetic field, said circuit controlled by a plurality of said track relays, to change its characteristics in accordance with changes in traffic conditions in said blocks, a single electron tube device on said vehicle inductively responsive to the magnetic field of said trackway means, a circuit on said vehicle controlled by said electron tube device in accordance with the characteristics of the circuit energizing said trackway means and a signal device controlled by said vehicle circuit and arranged to change its indication as the

characteristics of the circuit energizing said trackway means is changed.

106. In a railway traffic controlling system, in combination, a railway track, trackway means energized solely by a single circuit for producing a magnetic field, means on the trackway controlling said circuit to change its characteristics, a vehicle on said track having an electron tube device inductively responsive to the magnetic field of said trackway means, a circuit on the vehicle controlled by said electron tube device in accordance with the characteristics of the circuit energizing said trackway means and 15 a translating device having a plurality of energized conditions selectively controlled by said vehicle circuit.

107. In a railway traffic controlling system, in combination, a railway track, trackway means energized by a circuit for producing a magnetic field, means on the trackway controlling said circuit to change its characteristics, a vehicle on said track, an electron tube device on said vehicle responsive to the magnetic field of said trackway means, a circuit on said vehicle controlled by said electron tube device in accordance with the characteristics of the circuit energizing said trackway means and a translating device having a plurality of energized conditions controlled only by said vehicle circuit and selectively responsive to said characteristics.

108. In a railway traffic controlling system, in combination, a railway track, a vehicle thereon, a device on the trackway controlled by traffic conditions, a device on said vehicle inductively responsive to said trackway device, a normally energized relay on 35 said vehicle controlled by said vehicle device and deenergized by said trackway device, a second relay on said vehicle controlling said normally energized relay, a translating device on said vehicle energized in the proceed 40 position, a circuit for energizing said translating device and means for establishing conditions for closing said circuit by a contact on said normally energized relay in the energized position and a contact on said second 45 relay in the deenergized position.

109. In a railway traffic controlling system, in combination, a railway track, a vehicle thereon, a device on the trackway controlled by traffic conditions, a device on said 55 vehicle inductively responsive to said trackway device, a normally energized relay on said vehicle controlled by said vehicle device and deenergized by said trackway device, a second relay on said vehicle controlling said 60 normally energized relay and a translating device on said vehicle having a plurality of energized conditions, circuits for controlling said translating device and means for establishing conditions for closing said circuits by 65 said normally energized relay in the ener-

gized position and said second relay in the deenergized position.

110. In a train control system, in combination, a track with a vehicle thereon, trackway means selectively controlled by traffic conditions, means on said vehicle including an electron tube device inductively responsive to said trackway means, a cab signal on said vehicle giving clear, caution and stop indications, a relay on said vehicle selectively controlled by said trackway means through said inductive responsive means and when energized establishing conditions for a clear signal and when deenergized establishing conditions for the display of the caution signal. 70

111. In a train control system, in combination, a track with a vehicle thereon, trackway means selectively controlled by traffic conditions, means on said vehicle including a single electron tube device inductively responsive to said trackway means, a relay on said vehicle selectively controlled by said trackway means through said inductive responsive means, a second relay on said vehicle deenergized by said trackway means, a translating device on said vehicle having a proceed position established by an energized circuit, and means for establishing the circuit of said translating device by said first named relay deenergized and by said second named relay 80 85 energized.

112. In a train control system, in combination, a track with a vehicle thereon, trackway means selectively controlled by traffic conditions, means on said vehicle including a single electron tube device inductively responsive to said trackway means, a translating device on said vehicle having a proceed position established by an energized circuit, a pair of relays on said vehicle one of which is selectively controlled by said trackway device through said vehicle means and means for establishing the circuit of said translating device by one of said relays in the energized position and the other in the deenergized position. 100

113. In a train control system, in combination, a track with a vehicle thereon, trackway means selectively controlled by traffic conditions, means on said vehicle including an electron tube device inductively responsible to said trackway means, a translating device on said vehicle controlled by an electric circuit, a pair of relays on said vehicle controlled by said trackway means through said vehicle means and at least one of said relays being selectively responsible to said trackway means and means for establishing the circuit of said translating device when said selectively operated relay is in the deenergized position 115 120 and the other relay is energized. 125

114. In a train control system, in combination, a track with a vehicle thereon, said track divided into blocks, means on the trackway selectively controlled by said blocks in 130

accordance with traffic conditions, means on said vehicle including an electron tube device inductively responsive to said trackway means, a signal device on said vehicle giving a caution and a stop indication, electric circuits controlling said signal device, a pair of relays on said vehicle controlled by said trackway means through said vehicle means and at least one of said relays being selectively responsible to said trackway means in accordance with traffic conditions and means for establishing the circuit for the caution indication of said signal by a back contact on the selectively responsive relay and by a front contact on the other relay.

115. In a train control system, in combination, a track with a vehicle thereon, said track divided into blocks, means on the trackway selectively controlled by said blocks in accordance with traffic conditions, means on said vehicle inductively responsive to said trackway means, a signal device on said vehicle giving a caution and a stop indication, electric circuits controlling said signal device, a pair of relays on said vehicle controlled by said trackway means through said vehicle means and at least one of said relays being selectively responsive to said trackway means in accordance with traffic conditions, the circuit for the caution indication of said signal device being established by a back contact on the selectively responsive relay and by a front contact on the other relay and the circuit for the stop indication of said signal device being established by a back contact on the said other relay.

Signed at New York city, in the county of New York, and State of New York, this 28th day of September A. D. 1921.

JOHN S. HOLLIDAY.
